UNITED STATES PATENT OFFICE.

ALBERT MAURICE AUBERT, OF BILLANCOURT, FRANCE.

FURNACE.

1,353,818.

Specification of Letters Patent. Patented Sept. 28, 1920.

Application filed April 26, 1918. Serial No. 230,996.

To all whom it may concern:

Be it known that I, ALBERT MAURICE AUBERT, citizen of the Republic of France, residing at 3 Rue de la Ferme, Billancourt, Seine, in the said Republic, engineer, have invented certain new and useful Improvements in Furnaces; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to improvements in furnaces, more specifically to rotating and other furnaces comprising two parts which are adapted to move relatively to each other on the path of the flame or hot gases.

In such apparatus the junction between the two parts of the furnace requires to be made in such a manner that the losses of heat are as small as possible or so that the fall of temperature is a predetermined quantity and moreover that the solid materials more or less melted which are carried along do not bind the two parts of the furnace together, which would interfere with their necessary relative motion.

This invention fulfills the conditions while procuring other advantages as will be hereafter explained.

Several modes of applying the invention are shown on the accompanying drawing.

Figure 1 of this drawing is a longitudinal section of the two parts of a furnace which are adapted to move relatively to each other.

Figs. 2, 3 and 4 are similar views representing different modifications.

Fig. 5 is a view in longitudinal section of a tilting furnace with my invention applied thereto.

In all cases the invention consists in leaving a free interval between the two parts *a* and *b* of the furnace which must move relatively to each other, the surrounding air alone forming an air joint owing to the fact that it is not carried along with the flame or is carried along only to a certain extent which is determined by the structure of the above mentioned parts.

The openings *c* and *d* in the parts *a* and *b* respectively have the same center line as the flame jet which latter possesses a suffi-

cient speed to enable it to pass through the interval and go from *c* to *d* without materially expanding laterally.

If the openings *c* and *d* have the same diameter, as shown by Fig. 1 of the drawing, no air is carried along with the flame, the air simply forming a joint to prevent the loss of heat.

Whenever a certain quantity of air is wanted to be carried along into the part *b*, the opening *d* is made more or less conical at the mouth, according to the quantity of air required, as shown by Fig. 2.

If more air is to be carried into *b*, because a larger quantity is required for the process performed there, then the opening *d* is made straight but it is given a larger diameter than to *c*, as shown by Fig. 3.

Or else, for the same purpose the openings *c* and *d* may have the same diameter on most of their lengths but the outer portion of the opening *c* in the part *a* of the furnace be made conical or of a reduced sectional area, as shown by Fig. 4.

It will be easily understood that in a furnace made according to this invention the losses of heat will really be such as predetermined by the structure. As to the materials more or less melted that are carried along, they will fall down by themselves or will be removed by the attendant at the gap between the parts *a* and *b*; therefore there will be no risk of these parts adhering to each other and their relative motion being interfered with.

In Fig. 5, *B* is a tilting furnace, *C* the charging door, *D* the discharge orifice and *E* the fuel valve controlling the admission of fuel, as tar, from the fuel heating coil *G*.

The furnace is mounted on a frame *E* so as to tilt while keeping the ports *a* and *b* in alinement, the port *b* conducting the gases to the chamber *F* connected to a stack, as is customary. The coil for heating the fuel is contained in the chamber *F* and is heated by the gases leaving the furnace.

In addition to the advantages above mentioned the device permits to see, on the way of the flame or hot gases, how the industrial process being conducted is progressing and this makes it possible to properly adjust the combustion and the rapidity of the process as also the oxidizing or reducing atmosphere of the furnace.

Moreover, the device gives the two parts

of the furnace every liberty of expanding while otherwise such expansion might prevent their relative motion.

Finally, the keeping of a furnace in good order is made very easy by this invention, as the latter does away with any sealing material liable to destruction.

I claim:

1. A metallurgical tilting furnace having a gas port and an alined port, one of said ports rotatable relatively to the other and separated from each other by an open space sufficient for viewing the flame under all conditions of operation and surrounded by air, the gas current from one port to the other being sufficient to maintain the passage of gas without being diverted through said space.
2. A metallurgical furnace having a rotatable gas port for the passage of gas and a stationary port, said ports of different effective diameters being in alinement and separated from one another by an open space visible under all conditions of operation and

surrounded by air, the gas current from one port across said space to the other port of the furnace being sufficient to prevent diversion of gas through said space.

3. In a metallurgical apparatus having a stationary gas port and a tilting furnace having a port in alinement with the aforesaid port, the port from which the gas issues being constricted with respect to the port receiving gas in its flow direction therefrom, said ports being spaced axially from one another sufficient to permit the gas current to be visible under all conditions of operation, whereby air will be drawn from the space between the ports by the gas current into the larger port.

In testimony that I claim the foregoing as my invention, I have signed my name in presence of two subscribing witnesses.

ALBERT MAURICE AUBERT.
